UNITED STATES PATENT OFFICE.

ABRAHAM L. A. HIMMELWRIGHT, OF NEW YORK, N. Y., ASSIGNOR TO THE NEW JERSEY WIRE CLOTH COMPANY, OF TRENTON, NEW JERSEY, A CORPORATION OF NEW JERSEY.

CENTERING CONSTRUCTION.

No. 830,150.

Specification of Letters Patent.

Patented Sept. 4, 1906.

Application filed June 9, 1905. Serial No. 264,415.

To all whom it may concern:

Be it known that I, ABRAHAM L. A. HIMMELWRIGHT, a citizen of the United States, residing at New York, county of New York, 5 and State of New York, have invented certain new and useful Improvements in Centering Construction, fully described and represented in the following specification and the accompanying drawings, forming a part of 10 the same.

This invention relates to the construction of fireproof floors, ceilings, arches, partitions, walls, and similar structures in which a temporary framework or centering is used to 15 support the material of the structure during the making of the same and during the setting of the concrete or other plastic material, if the structure be made of plastic material, the object of the invention being to provide 20 a simple, cheap, and efficient centering construction readily put in place and removed and by which the use of supporting beams, bucks, or frames, such as are usually employed for supporting the centering-boards, 25 is avoided.

For a full understanding of the invention a detailed description of a construction of the preferred form embodying all the features of the same as applied in connection with a concrete 30 floor will now be given in connection with the accompanying drawings, forming a part of this specification, and the features forming the invention then particularly pointed out in the claims.

In the drawings, Figure 1 is a section transversely to the beams, showing the floor before removal of the centering with the concrete omitted from part of the view. Fig. 2 is a sectional plan of Fig. 1 with the concrete 40 removed. Fig. 3 is a section longitudinally of the beams on the line 3 of Fig. 1. Fig. 4 is a view similar to Fig. 1, showing the complete floor with the centering removed and with the usual plaster finish.

Referring to the drawings, A represents the beams, shown as of the common I form, and B the usual metal bars extending from beam to beam and acting to support and strengthen the floor concrete C. These bars are shown 45 as similar to those of patents granted to John W. Rapp, No. 537,483, No. 557,147, and No. 631,941, this form of bar being preferred on account of its strength and light-

ness; but it will be understood that bars of other forms may be used in connection with 55 the present invention.

The floor shown is of the curved-arch form and the bars B are supported on the bottom flanges of the beam, as usual in such constructions, with spanners D, acting as 60 convenient spacers for the bars B and to hold the bars in position, these spanners being shown as of a common form consisting of metal strips looped over the tops of the bars.

The invention may be used without the 65 concrete extending about the bottom flanges of the beams; but preferably in such concrete floors the concrete will be extended downward about the lower flanges of the beams, so as to protect the beam-flanges below the metal bars B, as shown, and the concrete on the under sides of the beams will 70 preferably be supported by the clips x, arranged at intervals along the beams and having arms embedded in and acting to support 75 the concrete, as shown, and as fully described and claimed in United States Letters Patent No. 786,289, April 4, 1905.

Referring now to the centering used for supporting the concrete during filling in and 80 setting, this centering is formed of the usual boards E, which in accordance with the present invention are secured to and supported directly from the bars B by ties 10 of wire or similar material of sufficient strength 85 to support the centering while adapted to be readily cut for the removal of the centering. A quick and convenient way of building the centering is that shown, in which the centering-boards E extend longitudinally of the 90 beams and continuous wires are used for tying the centering-boards to the bars, these wires being tied around the bars at one end and then being passed successively under a centering-board, then over the bar B downward and under the next centering-board 95 and over the bar B, and so on as the successive centering-boards are put in position until the centering is completed. The course of the wires is shown in Fig. 2. The 100 soffit-box, consisting of the bottom board and two side boards inclosing the bottom of the beam below the bars B, is supported by wires 10, which are passed under the soffit-box and tied about the bars B, or these wires 105 may be continuous with the wires by which

the other centering-boards are supported. It will be understood, however, that the method of applying the wire to support the centering-boards may be varied, the essential feature consisting in the support of the centering-boards directly by the bars B by ties adapted to be cut for the removal of the centering, thus avoiding all use of centering beams, frames, or complicated supporting devices for the centering-boards.

For removing the centering it is necessary only to cut the ties on the under side of the centering-boards and the whole centering will drop directly away from the concrete,

15 leaving the upper portions of the ties in the concrete. If the usual plaster finish F be used, as shown in Fig. 4, the wires and clips D will be wholly covered and concealed, or the usual suspended ceiling of metal lathing 20 and plaster may be supported from the beams below the floor and beam protection.

It will be understood that the invention is not limited to floors or other horizontal structures, but that the broader features of 25 the invention may be applied also in building partitions or walls, the centering-boards being supported by being tied to the usual vertical wall-studs or other metal frame of the partition or wall and being removed by 30 cutting the ties, as above described.

What I claim is—

1. The combination with metal bars forming a part of a permanent framework, of a centering formed by boards extending transversely to the bars and secured directly to said bars by ties adapted to be cut to release the centering-boards for their removal.

35 2. The combination with metal bars forming a part of a permanent framework, of a

centering formed by boards extending transversely to the bars and secured directly to said bars by wires passed around said bars and around the successive centering-boards, whereby the centering-boards may be removed by cutting the wires. 45

3. The combination with beams or the like, of metal bars extending between the beams and supported thereby, a centering formed by boards extending longitudinally of the beams and on the under side of said 50 bars and secured directly to the bars by ties adapted to be cut for the removal of the centering.

4. The combination with flanged beams, of bars extending between the beams and 55 supported on the bottom flanges of the beams, a centering formed by boards extending longitudinally of the beams and on the under side of said bars, soffit-boxes inclosing the bottom flanges of the beams, and wire 60 ties supporting the centering-boards and soffit-boxes directly from the metal bars.

5. The combination with the beams A, of bars B extending from beam to beam, a centering formed by boards E extending longitudinally of the beams and on the under side of the bars, and ties 10 passing around the bars and under the successive centering-boards and by which the centering-boards are supported directly from the bars. 65

In testimony whereof I have hereunto set my hand in the presence of two subscribing witnesses.

ABRAHAM L. A. HIMMELWRIGHT.
